Primary Examiner — Lauren D McVey

(57) **CLAIM**

The ornamental design for a handheld printer, as shown and described.

DESCRIPTION

FIG. 1 is an isometric view of a handheld printer, showing our design; and

FIG. 2 is an isometric view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

Broken lines are included in FIGS. 1, 2, 3, and 5–8 to depict bisecting lines and internal elements of the handheld printer which form no part of the claimed design.

1 Claim, 8 Drawing Sheets
